UNITED STATES PATENT OFFICE.

FRITZ KESSELRING, OF NEUHAUSEN, SWITZERLAND.

CONTINUOUS-CURRENT DYNAMO.

1,389,051.

Specification of Letters Patent. Patented Aug. 30, 1921.

Original application filed July 17, 1916, Serial No. 109,800. Divided and this application filed June 12, 1920. Serial No. 388,699.

To all whom it may concern:

Be it known that I, FRITZ KESSELRING, a citizen of the Swiss Confederation, residing at Neuhausen-on-the-Rhine, Switzerland, have invented a new and useful Continuous-Current Dynamo, for which I have filed applications in Austria May 18, 1916; in Great Britain June 8, 1916; in Hungary June 9, 1916, of which the following is a specification.

The invention relates to variable speed generators, where an approximately constant voltage is to be obtained at variable speed, without the provision of accessories, such as controlling resistances or the like.

It is an object of the invention to provide special means for obtaining automatic regulation of the generator during speed variations, so that at all times a constant voltage may be obtained, such as is necessary in train illumination, where the generator is driven by the shaft of the running wheels.

To the accomplishment of the principal object and others that will become apparent upon perusal of the specification and claims forming a part thereof, the preferred embodiments of the invention are illustrated in the accompanying drawing, in which:

Figures 1 and 2 illustrate the curves of the different magnetic fluxes in the dynamo.

Fig. 3 indicates a two pole dynamo having main and auxiliary poles, the latter being provided with two sets of field coils.

Fig. 4 indicates the dynamo provided with main and auxiliary poles, and an armature having two separate windings.

This invention is a division of my copending application for Letters Patent of the United States, for improvements in continuous current dynamos, filed July 17, 1916, Serial No. 109,800, patented July 13, 1920, No. 1,346,213.

The E. M. F. $E = C_1 \varphi n$, wherein—

E is the E. M. F. induced in the armature of a generator,

φ the resultant magnetic flux of the armature per pole pitch (periphery of the armature divided by the number of poles),

n the number of revolutions per minute, and C_1 a constant.

It is immaterial in what manner the magnetic flux φ is produced, and either an electromagnet, or a permanent magnet, or a combination of both may be adopted, constituting the field poles of the machine. To ob-

tain a constant E. M. F. when the speed varies, it is necessary, of course, that the product $C_1 \varphi n$ should remain constant, and in view of the fact that the speed varies, φ must change, such that the product will always remain the same, in other words, φ must vary inversely as the number of revolutions n . To accomplish this end, the magnetic flux φ is produced in the present instance by at least two component fluxes, namely (1) a constant main flux φ_1 , which is produced either by a permanent magnet, or by an approximately constant number of ampere turns, or by a combination of both, and (2) a variable, auxiliary flux φ_2 directed oppositely to the main flux φ_1 , and produced by a number of ampere turns $a^w n$ computed according to the formula: $a^w n = C_2 n - C_3$, wherein C_2, C_3 are constants and the constant C_3 may be zero.

The ampere turns of the auxiliary field poles, constituting the M. M. F. $C_2 n$ and producing the magnetic flux φ_2 varies directly as the number of revolutions, whereas the M. M. F. C_3 is approximately constant. The part $C_2 n$ directly in proportion to the speed produces in the air space a flux opposite to the direction of the flux φ_1 , produced by the main field poles. The portion C_3 of the ampere turns provided on the auxiliary field poles is arranged to produce a magnetic flux of the same direction as the main flux. The ampere turns C_3 can, of course, also be replaced either wholly or in part by a permanent magnet, or, if preferred, they may be entirely dispensed with.

If C_3 were zero the φ -curve would have the form of the dotted line shown in Fig. 1, R being the residual magnetism of the auxiliary magnetic circuit. As may be seen, this curve is not inversely proportionate to the number of revolutions and would therefore not give a constant voltage. This curve would also make necessary a large and costly dynamo and for this reason it is important that C_3 is different from zero.

The approximately constant ampere turns of the main field poles producing the main flux φ_1 , are obtained in the known manner by one or more windings energized by an approximately constant voltage. Or the flux is obtained by a permanent magnet, constituting main field poles, or by a combination of both arrangements. The same applies to the constant portion C_3 of the auxiliary flux.

ϕ_2 . It may also be obtained by introducing into the circuit containing the ampere turns C_2n an approximately constant voltage of proper direction.

5 Thus, the ϕ_2 flux is obtained by two operative E. M. F.'s, one varying directly as the speed, and the other being approximately constant. The approximately constant flux of the C_2n circuit can be employed in combination with permanent magnets as well as with approximately constant additional ampere turns.

10 The ampere turns C_2n , varying directly as the number of revolutions, can also be obtained by arranging an armature winding adapted for direct current or a portion of such a winding to rotate at a speed proportional to the number of revolutions of the generator in an approximately constant 15 magnetic field (for instance the main magnetic flux of the generator), and by applying the induced voltage of one or more exciter windings.

15 Another modification embodies the regulating of auxiliary poles so that they become magnetized by the armature winding or by conducting the current of the armature around the auxiliary poles, or a combination of both means may be provided. In both 20 cases the current of the armature is not constant and varies approximately proportional to the number of revolutions. These modifications, therefore, are of secondary importance and will only be resorted to in the 25 case of small type machines.

30 The two fluxes ϕ_1 and ϕ_2 may flow in entirely different paths, and in this case care is to be taken that the conductors of the armature of the dynamo should cut both fluxes. Conversely, the fluxes ϕ_1 and ϕ_2 may flow in paths a portion of which is common to both fluxes, and similarly fluxes can be set up by spaced poles to flow through the same yoke and the same armature (Fig. 4).

40 Referring to the drawings, Figs. 1 and 2 show the graphic curves of the different magnetic fluxes in the dynamo. ϕ_1 is the approximately constant main magnetic flux, ϕ_2 the variable auxiliary magnetic flux and ϕ the resulting flux. The number of revolutions n varies between n_1 and n_2 , constituting the range of speed variations for the dynamo. C_2n and C_3 are the M. M. F.'s which produce the auxiliary flux. The curve ϕ_2 is 45 no other than the magnetization curve of the magnetic circuit of the auxiliary flux. By a suitable selection of substance (air, cast steel, gray iron, armature iron, etc.,) as well as the transverse section of the auxiliary 50 magnetic flux circuit, it is possible, as known, to change the form of the curve ϕ_2 . Consequently, it is always possible to obtain a curve ϕ which is nearly inversely proportionate to the number of revolutions. In Fig. 2 55 it is assumed for the sake of example that ϕ_1

is not exactly constant but rises slightly with an increasing number of revolutions. In this case also by choosing an appropriate characteristic for the auxiliary magnetic circuit it is possible to obtain a good ϕ curve.

60 In Figs. 3 and 4 the application of the invention is diagrammatically illustrated. The generator shown in Fig. 4 comprises the armature A and produces the main magnetic flux ϕ_1 and the auxiliary flux ϕ_2 by means of field coils E_1 , E_2 , E_3 . The main armature winding W_1 is connected with the armature brushes K_1 and K_2 . The auxiliary winding W_2 is connected to the commutator brushes K_3 and K_4 . In Fig. 3, K_3 is an auxiliary 65 brush on the main commutator. In order to simplify the diagrammatic views all switches have been omitted.

70 The generator indicated in Fig. 3 comprises a two pole dynamo electric machine, the main brushes K_1 and K_2 being in the neutral zone. In each pole pitch a main pole producing the flux ϕ_1 and an auxiliary pole producing the flux ϕ_2 are arranged. Between the main brushes an auxiliary 75 brush K_3 is provided on the commutator. The armature is equipped with one armature winding only. The main pole is adapted to produce an approximately constant magnetic flux, whereas the auxiliary pole produces a variable magnetic flux flowing in a direction opposite to that of the main flux. The main pole is equipped with the main field coil E_1 , connected to the brushes K_1 and K_2 . The auxiliary pole is equipped 80 with two field coils E_2 , E_3 , of which the former is connected with the brushes K_1 and K_3 . As the armature coils between the brushes K_1 and K_3 cut only the approximately constant flux ϕ_1 , it is evident that 85 between K_1 and K_2 a voltage C_2n is produced proportional to the number of revolutions. The field coil E_3 is connected to a source of 90 approximately constant E. M. F. such as the main brushes K_1 and K_2 or a storage battery. The auxiliary pole is equipped 95 with two field coils E_2 , E_3 , of which the former is connected with the brushes K_1 and K_3 . As the armature coils between the brushes K_1 and K_3 cut only the approximately constant flux ϕ_1 , it is evident that 100 between K_1 and K_2 a voltage C_2n is produced proportional to the number of revolutions. The field coil E_3 is connected to a source of 105 approximately constant E. M. F. such as the main brushes K_1 and K_2 or a storage battery. The auxiliary pole is equipped 110 with two field coils E_2 , E_3 , of which the former is connected with the brushes K_1 and K_3 . As the armature coils between the brushes K_1 and K_3 cut only the approximately constant flux ϕ_1 , it is evident that 115 between K_1 and K_2 a voltage C_2n is produced proportional to the number of revolutions. The field coil E_3 is connected to a source of 120 approximately constant E. M. F. such as the main brushes K_1 and K_2 or a storage battery. The auxiliary pole is equipped 125 with two field coils E_2 , E_3 , of which the former is connected with the brushes K_1 and K_3 . As the armature coils between the brushes K_1 and K_3 cut only the approximately constant flux ϕ_1 , it is evident that 130 between K_1 and K_2 a voltage C_2n is produced proportional to the number of revolutions.

135 The dynamo illustrated in Fig. 4 comprises main poles and auxiliary poles admitting the main flux ϕ_1 and the auxiliary flux ϕ_2 , respectively. The armature A is provided with two windings, namely, the main armature winding W_1 equipped with the commutator brushes K_1 and K_2 and an auxiliary armature winding W_2 having the commutator brushes K_3 and K_4 . The main winding is adapted to revolve within both magnetic fluxes ϕ_1 and ϕ_2 , the auxiliary 140

winding W_2 is adapted to revolve only within the constant flux φ_1 so as to produce a voltage which is proportional to the number of revolutions. The main pole contains 5 a main field coil E_1 connected to the main brushes K_1 and K_2 and producing the approximately constant magnetic flux φ_1 . The field coil E_2 of the auxiliary pole is impressed with the difference of voltage 10 existing between the auxiliary armature winding and the main armature winding. The voltage of the auxiliary armature is proportional to the number of revolutions and the voltage of the main armature is approximately constant. It is therefore 15 evident that the M. M. F. of the auxiliary pole is $C_2n - C_3$. The magnetizing effect of the auxiliary field coils is opposed to that of the main field coils and in view of the 20 magnetization curve of the auxiliary pole (Figs. 1 or 2) it is evident that the voltage produced by the main armature winding is approximately constant.

It is within the scope of the invention 25 to provide on the auxiliary pole in addition to the field coil E_2 a third field coil energized by the main armature winding, to increase the constant C_2 .

If a strictly constant voltage is not required, but rather a voltage which rises or falls slightly with the number of revolutions, this may be obtained by a suitable selection of the materials, etc., for the auxiliary magnetic circuit. For example, in 30 the case of train illumination it is sometimes required that upon greater speed the lights should shine brighter, and in such cases the voltage is permitted to rise slightly with the increasing number of revolutions. 35 It is, of course, impossible to produce a φ curve which conforms closely to the ideal φ curve, and for this reason certain deviations from the desired voltage curve must be taken into consideration.

40 45 What I claim is:—

1. A variable-speed continuous current dynamo having two main magnetic poles the strength of which is substantially independent of the speed variations, in alternate arrangement with said main magnetic 50

poles, two auxiliary poles, a two-pole armature relatively movable at a variable speed within said main and auxiliary poles, two main brushes on said armature, an auxiliary brush on said armature between the main 55 brushes, and means for producing in said auxiliary poles two magneto-motive forces, one proportionate to the number of revolutions and the other approximately constant, said means comprising two sets of field coils 60 energizing said auxiliary poles, the first of the two sets of coils being connected to said auxiliary brush and to one of the main brushes, the armature between said auxiliary and said main brush being affected by 65 the magnetic lines of force of the main poles only and the second of the two sets of coils being connected to said two main brushes in such a manner that the magnetizing effect of said second set of coils is 70 opposed to the magnetizing effect of said first set of coils.

2. A variable-speed continuous current dynamo having two main magnetic poles the strength of which is substantially independent of the speed variations, in alternate arrangement with said two main magnetic poles, two auxiliary poles with coils 75 energizing said auxiliary poles, a two-pole armature relatively movable at a variable 80 speed within said main and auxiliary poles, two main brushes on said armature, and means for producing in said auxiliary field coils two electro-motive forces respectively, one proportionate to the number of revolutions and the other approximately constant, said means comprising an auxiliary brush between the two main brushes, one of said 85 auxiliary field coils being connected to said auxiliary brush and to one of the two main brushes, the armature between said auxiliary and said main brush being affected by the magnetic lines of force of the main poles only, and also comprising a suitably directed 90 approximately constant voltage source introduced into the circuit of the other of said auxiliary coils.

In witness whereof I affix my signature.

FRITZ KESSELRING.
